Fig. 3.

Fig. 5.

FIG. 1 is an isometric view of a vehicle wheel center unit showing my new design;

FIG. 2 is a front view of the center unit of FIG. 1;

FIG. 3 is a back view of the center unit of FIG. 1;

FIG. 4 is a cross-sectional view of the center unit of FIG. 1 taken along line 4—4 of FIG. 2; and

FIG. 5 is a front view of a modified form thereof, it being understood that other views thereof would be the same as shown in FIGS. 1 through 4.

The rim shown in broken lines in FIG. 1 is included for illustrative purposes only.

The characteristic feature of my design resides in the specific appearance of the spokes having a flat triangular shaped top surface integrally formed upon an arcuate spoke as shown.

I claim:

The ornamental design for a vehicle wheel center unit, substantially as shown and described.
